TELEPRINTER RECEIVER DEVICE

Herbert Wüsteney, Kladow, Germany, assignor to
Siemens & Halske, Aktiengesellschaft, Siem-
mensstadt near Berlin, Germany, a German
corporation

Application October 5, 1950, Serial No. 188,614
In Germany November 12, 1948

9 Claims. (Cl. 178—33)

1

This invention relates to remotely controlled signal receiver apparatus, and particularly to teleprinters operating in accordance with the start-stop principle.

A brief review of the pertinent prior art is rendered below to furnish a basis for a better understanding of the invention.

In teleprinters operating in accordance with the start-stop principle, the switching-in of the apparatus and the sensing of the individual (5 10 or 6) symbol steps is initiated by magnets which are remotely controlled over the line. The release of the control shaft serving the switching-in of the receiver apparatus requires considerable energy, while small parts and relatively small energies are desired for executing the rapid motions in the control of the selective steps, that is, in the sensing of the individual symbol steps.

Known teleprinters operating in accordance with the five-step alphabet are provided with a receiver magnet having five armatures, one for serving in the sensing of each selective step. The armatures are by magnetic means placed in operative position in definite succession for the sensing of the individual current steps. While such receiver devices operate quite reliably, they require a great number of individual parts and very accurate adjustments.

In other known apparatus of this type there is provided only one armature with means for determining the energy and the working stroke for the release, that is, for the switching-in of the apparatus, thus requiring very considerable working energy. Apparatus of this kind are very noisy in operation and are subjected to a great deal of wear and tear.

The object of the invention is to provide a receiver device of very simple construction having a small number of parts and improved electric sensitivity.

This object is realized by equipping the receiver magnet with two armatures, one having a relatively large stroke for the release of the control shaft and one having a relatively small stroke for governing the control of the selection operations. The sensing operations in an embodiment made in accordance with the invention are accomplished for all symbol steps by a single selection armature, and are mechanically distributed and transformed to serve the setting or adjustment of the printer means.

The object noted above and additional objects and features will be brought out in the course of the detailed description of an embodiment of the invention, which will be presently rendered

2

with reference to the accompanying drawings. In these drawings,

Fig. 1 shows in schematic manner essential parts for accomplishing the objects of the invention in a teleprinter operating in accordance with the five-step alphabet, and illustrates in diagrammatic side view particularly the structure of the parts required for obtaining the selective operations governed by the armature having a small working stroke;

Fig. 2 represents in diagrammatic manner the structures of the cams which are arranged upon the control shaft for governing the selective operations;

Fig. 3 is a diagrammatic end view of the arrangement shown in Fig. 1; and

Fig. 4 illustrates diagrammatically the parts controlled by the armature having a large working stroke and serving for the release of the receiver shaft into operating position.

Like parts are numbered alike throughout the drawings. Known elements and details will be referred to only to the extent required for explaining the invention.

25 The receiver magnet is indicated in the drawings by numeral 1. Numeral 2 (Fig. 4) shows the armature having a large working stroke for controlling the release of the receiver shaft into operating position. The armature having a small working stroke and governing the selection operations is indicated at 3 (Fig. 1). The two armatures 2 and 3 are pivotally mounted on the common shaft 4. The armature 2 is provided with a strong restoring spring 5, while the restoring spring 6 for the armature 3 is considerably weaker. Upon the armature 2 is provided the lever arm 7 carrying at its upper end a locking ear 8 and at its lower end an extension 9, the latter being operative to press the armature 2 against the core of the receiver magnet 1 at the conclusion of each revolution of the receiver shaft 28 under the control of the cam 10 which is carried by the receiver shaft. The lever arm 11 is provided for locking the receiver shaft 28 by operative locking coaction of its upper end with the locking ear 8 in attracted position of the armature 2. The winding of the receiver magnet 1 is disposed in the telegraphic circuit, keeping the magnet energized, its armature 2 attracted, and the receiver shaft 28 is consequently locked against operation. The circuit is interrupted for the purpose of releasing the receiver shaft for operation, and upon such interruption the armature 2 releases and the locking ear 8 is retracted to release the lever arm

11. The tooth $12a$ formed by the cam 12 , which is carried by the receiver shaft 28 , now presses against the tooth $11a$ formed by the lever 11 , against the slight pressure of the spring 13 , causing counterclockwise angular displacement of the lever 11 around its pivot, and the shaft 28 can now execute one full revolution. At the conclusion of such revolution the cam 10 engages the lower end 9 of the lever arm 7 and presses the armature 2 against the core of the receiver magnet 1 , as mentioned before. The locking ear 8 is thus positioned against the upper end of the lever arm 11 , which has meanwhile assumed the position shown in Fig. 4, due to the pull of the spring 13 , and thus locks the receiver shaft against rotation at the conclusion of each revolution.

The selection control arrangement, essential elements of which are diagrammatically shown in Figs. 1 and 3, comprises the armature 3 , the selection lever 14 and five angular control levers 17 . Each such lever is connected with its associated control member 18 by a ball-and-socket journal 23 . The arms $3a$ and $14a$ of the armature 3 and the lever 14 , respectively, and the right arms of the angular levers 17 are governed by the cams 29 , 30 and $n1-n5$, respectively, all of which are mounted on the receiver shaft 28 . Being on the same shaft, these cams are arranged one in back of the other, as seen in Fig. 1. In order to indicate their structures more clearly, they have been shown in Fig. 2 separately, one next to the other. The selection lever 14 , which is pivoted on the shaft 27 , carries an ear 15 which is in normal position disposed in front of and slightly above the free end of the arm 16 extending from the armature 3 . At its lower end the lever 14 carries a bar 19 (see also Fig. 3) which governs the operation of the five control members 18 . These members operate in the manner of tilting levers, each member actuating a generally T-shaped member 24 which engages a slot in its associated selection bar 25 .

The arrangement explained above with reference to Figs. 1-3 operates as follows:

In resting position, and up to the sensing of the first symbol step, the selection armature 3 is held against the receiver magnet 1 by the cam 29 . Depressions formed by the cam permit the armature to fall into release position for each step. Immediately thereafter the selection lever 14 , whose extension $14a$ attempts to follow the control curve of the cam 30 , moves counterclockwise in the direction of the armature. In case the armature 3 is held incident to the first symbol step, the ear 15 of the lever 14 will pass freely adjacent the free end of the arm 16 extending from the armature 3 . However, if the armature has been released, the ear 15 will encounter the extension 16 of the armature, since the latter is angularly clockwise displaced by the action of the spring 6 , and the counterclockwise displacement of the lever 14 is thus intercepted and stopped. At the same time the first one of the five control levers 17 is displaced clockwise, as seen in Fig. 1, by its cam $n1$ (Fig. 2) for the selection of the first symbol step, pulling its associated control member 18 to the right. At the conclusion of this motion the edge 21 of the control member 18 glides along the pin 22 , cancelling any previous displacement of the arm 18 . During the return motion of the lever 17 and therewith the control member 18 , the lever 14 senses the position of the armature 3 . The lever 14 leaves the position of the control member 18 75

unaltered if its ear 15 encounters the extension 16 in released position of the armature 3 ; but, if the armature has remained attracted during the first step, the lever 14 can execute its full motion and presses the control member 18 to the right by means of the bar 19 . Leaf springs are in known manner (not illustrated) provided in connection with each ball-and-socket journal 23 , causing each control member 18 to remain in the position into which it was brought before actuation by the bar 19 and before engagement with the T-shaped member 24 . The setting or adjustment operations for each of the remaining four arms 18 take place in similar manner. The levers 17 fall shortly before the conclusion of one revolution of the receiver shaft simultaneously into corresponding depressions in their associated cams $n1-n5$ (Fig. 2) so that the lower arms of these levers 17 continue the clockwise downward motion, each pressing its associated control member 18 more or less to the right or to the left, depending on its setting or adjustment. The lower ends of the members 18 are thus caused to coact with the right or left ends, respectively, of the associated T-shaped member 24 , thereby correspondingly setting the coacting selection bars 25 .

It will be seen from the foregoing explanations that the selection device requires only a small number of individual parts which may be made lightweight due to the relatively small forces which are effective for executing the selection operations. A working stroke of about 1 mm. will suffice for the selection armature 3 , and the pull of its restoring spring 6 may be on the order of about 25 grams. The release armature 2 may have, on the other hand, a stroke of about 5 mm. and the pull of its restoring spring 5 may be on the order of about 70 grams. Since the armature 2 is, during the entire selection operation, widely spaced from the core of the receiver magnet, due to its large working stroke, it remains to all practical purposes ineffective so that the full energy of the receiver magnet 1 is available for the actuation of the selection armature 3 , thus requiring small current values for its energization.

A further advantage of the new arrangement resides in its ready adaptability for use in a structure operating in accordance with the six-step alphabet. All that is required for such use is merely an additional cam coacting with an associated control lever 17 and a control member 18 , and making the actuating bar 19 of the lever 14 correspondingly larger.

What is believed new and desired to have protected by United States Letters Patent is defined in the appended claims.

I claim:

1. In a start-stop teleprinter receiver a rotatable control shaft, a receiver magnet, a first and a second armature for coaction with said magnet, said first armature having a relatively large working stroke and said second armature having a relatively small working stroke, said first armature governing the operation of said control shaft by means comprising interlocking levers controlled thereby to release said control shaft for rotation through one revolution, and means operated by said control shaft at the conclusion of each revolution for pressing said first armature against the core of said magnet; and said second armature governing the selection operations by means comprising a first arm extending therefrom for cooperation with a control cam on said

control shaft which presses said armature against the core of said magnet during the revolution of said control shaft, a second arm extending from said second armature, a selection lever, a cam on said control shaft for causing said selection lever to move against said second arm, and interlocking means on said selection lever for coaction with said second arm whereby said selection lever is stopped in its displacement against said second arm by engagement therewith when said armature is in released position.

2. The arrangement and structure defined in claim 1, together with cam means carried by said control shaft for actuating the armature which governs said selection operations, said cam means forming depressions, one for the sensing of each symbol step, to cause said armature when in released position to follow successively thereinto during the rotation of said control shaft.

3. The arrangement and structure defined in claim 1, together with a plurality of selection bars, an operating member for each selection bar, and an actuating bar carried by said selection lever for operatively actuating said selection bars.

4. The arrangement and structure defined in claim 1, together with a plurality of selection bars, an operating member for each selection bar, an actuating bar carried by said selection lever for operatively actuating said selection bars, a lever for each operating member, and cam means carried by said control shaft for placing each such lever into preparatory position in accordance with a predetermined symbol step.

5. The arrangement and structure defined in claim 1, together with a plurality of selection bars, an operating member for each selection bar, an actuating bar carried by said selection lever for operatively actuating said selection bars, a lever for operatively affecting each operating member, and a common actuating bar for all operating members, whereby each operating member assumes one of two positions depending on its actuation by its associated lever alone or in conjunction with said actuating bar.

6. The arrangement and structure defined in claim 1, together with a plurality of selection bars, an operating member for each selection bar, an actuating bar carried by said selection lever for operatively actuating said selection bars, a lever for each operating member, and cam means carried by said control shaft for placing each such lever into preparatory position in accordance with a predetermined symbol step, said cam means being constructed and arranged to impart to said levers an additional motion prior to the

conclusion of a revolution of said control shaft to place said operating members in position for actuating said selection bars.

7. The arrangement and structure defined in
5 claim 1, together with a plurality of selection
bars, an operating member for each selection
bar, a control member for each operating mem-
ber, an actuating bar carried by said selection
lever for operatively actuating said control mem-
10 bers, a lever for each control member, cam means
carried by said control shaft for placing each
such lever into preparatory position in accord-
ance with a predetermined symbol step, each
operating member carrying two extensions for se-
15 lective coaction with a T-shaped member carried
by the associated selection bar.

3. The arrangement and structure defined in
claim 1, together with a plurality of selection bars,
a generally T-shaped operating member for each
20 selection bar, a control member for each operating
member, an actuating bar carried by said selection lever for operatively actuating said control members, a lever for each control member,
and cam means carried by said control shaft for
25 placing each such lever into preparatory position
in accordance with a predetermined symbol step,
each control member carrying two extensions for
selective coaction with the coacting T-shaped
operating member carried by the associated selection bar,
30 whereby each selection bar is actuated or retained in normal position, depending on the position of said extension of the associated control member.

9. The arrangement and structure defined in
35 claim 1, together with a plurality of selection
bars, an operating member for each selection
bar, an actuating bar carried by said selection
lever for operatively actuating said selection bars,
and a ball-and-socket joint for journaling each
40 selection bar for coaction with its associated
operating member.
